UNITED STATES PATENT OFFICE.

EDWARD JONES, OF NEW YORK, N. Y., ASSIGNOR TO THE AMERICAN PADDLE WHEEL COMPANY, OF SAME PLACE.

PADDLE-WHEEL FLOAT.

SPECIFICATION forming part of Letters Patent No. 247,654, dated September 27, 1881.

Application filed February 1, 1881. (No model.)

To all whom it may concern:

Be it known that I, EDWARD JONES, of the city, county, and State of New York, have invented a new and useful Improvement in Paddle-Wheel Floats; and I do hereby declare that the following is a full, clear, and exact description thereof, reference being had to the accompanying drawings, forming a part of this specification, in which—

10 Figure 1 represents a blade or bucket in elevation, and Fig. 2 a cross-section of the same on the line $\alpha\alpha$, embodying my invention. Fig. 3 represents a paddle-wheel provided with my improved floats.

15 This invention relates to that type of paddle-wheel in which the blades or buckets are arranged at an angle to the line of motion of the wheel, as shown in Letters Patent of the United States granted to me March 6, 1866, and numbered 53,008.

20 In said Letters Patent the blades or buckets are shown with increasing breadth of propelling-surface from the inboard or entering end to the outboard or emerging end, the lower edge 25 of the blade being formed in a convex curve.

This invention consists in constructing the blades or buckets in substantially the form described, and bending the same transversely or widthwise to present a convex propelling-surface.

30 In order that others may understand and apply my invention, I will first proceed to describe its construction and subsequently to set forth its advantages, and to point out in the 35 claim its novel features.

The blade or bucket represented in the drawings show substantially the form embodying

my improvement, the transverse convexity of the propelling-surface being clearly illustrated in Fig. 2, and intended to represent a degree 40 of transverse curvature of about two inches to each foot of breadth-surface.

The advantages resulting from such construction, when compared with a straight or inclined transverse surface, lie in avoiding the 45 great loss of power due to the action of the latter in passing through and emerging from the water in a circular path, and lifting large quantities of the same without deriving a propelling-force, and when used in the arrangement shown in my former Letters Patent referred to a perfect utilization of the motive power is secured by an increased number of revolutions of the wheels and an acceleration 50 in the speed of the vessel.

In applying my improved blade or bucket, one or more series may be used, if desired, as shown, for example, in Letters Patent of the United States granted to R D. Chatterton, July 24, 1844, No. 3,679.

60 Having thus fully described my invention, what I claim, and desire to secure by Letters Patent, is—

A paddle-wheel provided with one or more series of blades or buckets arranged at an angle 65 to the line of motion, constructed with increased breadth at or toward the outboard end and bent to present a transverse convex propelling-surface, substantially as described.

EDWARD JONES.
